(57) **CLAIM**

The ornamental design for an attachment for container candle, as shown and described.

DESCRIPTION

FIG. 1 is a perspective view of an embodiment of the attachment for container candle of the present invention.

FIG. 2 is a front elevational view of the attachment for container candle shown in FIG. 1.

FIG. 3 is a rear elevational view of the attachment for container candle shown in FIG. 1.

FIG. 4 is a right side elevational view of the attachment for container candle shown in FIG. 1 with the left side view being a mirror image thereof.

FIG. 5 is a top plan view of the attachment for container candle shown in FIG. 1; and,

FIG. 6 is a bottom plan view of the attachment for container candle shown in FIG. 1.

The broken lines shown in FIG. 1 are for the purpose of illustrating portions of the article that form no part of the claimed design.
